(57) CLAIM

An ornamental design for a mop and broom holder, as shown and described.

DESCRIPTION

FIG. 1 is a right side frontal perspective view of the mop and broom holder showing my new design.

FIG. 2 is a frontal view of FIG. 1.

FIG. 3 is a right side elevation view of FIG. 1.

FIG. 4 is a back view of FIG. 1.

FIG. 5 is a left side elevation view of FIG. 1.

FIG. 6 is a top view of FIG. 1;

FIG. 7 is a bottom view of FIG. 1; and,

FIG. 8 is a right side frontal environmental perspective view of the mop and broom holder.

The broken lines in FIG. 8 are for the purposes of illustration and form no part of the claimed invention.
